UNITED STATES PATENT OFFICE.

ABRAHAM GOLDSTEIN, OF PHILADELPHIA, PENNSYLVANIA, ASSIGNOR TO ELGIN
SILK WAIST CO., OF PHILADELPHIA, PENNSYLVANIA, A FIRM COMPOSED OF
WILLIAM GOLDSTEIN.

SUPPORTING AND EXHIBITING DEVICE FOR BOXES.

1,357,700.

Specification of Letters Patent.

Patented Nov. 2, 1920.

Application filed February 3, 1920. Serial No. 355,909.

To all whom it may concern:

Be it known that I, ABRAHAM GOLDSTEIN, a citizen of the United States, residing in the city and county of Philadelphia, State 5 of Pennsylvania, have invented a new and useful Supporting and Exhibiting Device for Boxes, of which the following is a specification.

My invention consists in providing a box 10 with a device for connecting articles therein, whereby they are adapted to be supported, and to retain their positions, and they may be exhibited to the best advantage while remaining in the box.

15 The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a box provided with a device embodying my invention for supporting articles therein.

20 Fig. 2 represents a central longitudinal section thereof.

Fig. 3 represents a perspective view of said supporting device.

Fig. 4 represents a perspective view of a 25 portion of the box, said supporting device being removed therefrom.

Similar numerals of reference indicate corresponding parts in the figures.

Referring to the drawings.

30 1 designates the body of a box which excepting the features of my invention applied thereto is of well known form and construction, the same being formed of paper, to which material, however, I do not limit 35 myself.

2 designates an open frame which is constructed of wire or other suitable material, the terminals of which are hooked or twisted together as at 3, thus uniting or interlocking said terminals and preserving the shape of the frame. In the front or outer corner portion of said frame is the loop 5 which, comprising a clamp member, is formed by bending the material on itself 45 inwardly and outwardly. In the bottom 6 of the body near said side is the opening 7, it being noticed that when the body is in upright position the side 4 becomes the top 50

thereof, and the bottom 6 becomes the back thereof.

55 The frame 2 is applied to the body as follows:—

The length 8 which comprises the top of the frame when in upright position is placed on the outer face of the side 4, 60 the side length 9 and the bottom length 10 of the frame enter the body within or below said side 4, and a portion of the length 10 passes through the opening 7 and joins the portion of the side 11 of the frame 65 on the exterior of the bottom 6. The terminal portion 12 of the side 11 extends from the length 8 and joins the terminal portion 13 of said side 11 on the exterior of the bottom 6, said terminals being interlocked or secured as at 3 as above stated, and thus the frame is firmly connected with 70 the body 1, and its shape is preserved.

The loop 5 embraces and clamps the edge portion of the side 4 of the frame and so 75 prevents lateral shifting of the front of the frame on said side.

It will be seen that the length 10 of the frame provides means within the body for attachment of a number of garment hangers thereto even while the body lies flat on its bottom, thus in a measure retaining the garments in place in the body, but when the body is placed in upright position the garments may be suspended from the frame and 80 so presented to view to the best advantage for purposes of exhibition and sale, as shown in Fig. 1, and the articles may be readily removed for handling when so desired.

As the length 8 of the frame is rested on 90 the side 4 of the body and the inner end of the length 10 is supported on the wall of the opening 6, the frame is sustained on the body and prevented from breaking down 95 therefrom. The length 10 is unbroken from end to end and presents a smooth surface for the hangers placed thereon, while the terminals of the frame are on the rear or underside of the body whereby they are concealed and they avoid presenting their cut 100 ends to the front.

Having thus described my invention what I claim as new and desire to secure by Letters Patent, is:—

1. A supporting and exhibiting device attachable to a box comprising a clamp con-

sisting of an open frame having means embracing an edge portion of a wall of the box, and whose members are a single unit and connected with relative portions of the box 5 providing a member within the box for the attachment thereto of an article to be supported and exhibited.

2. A supporting and exhibiting device attachable to a box comprising a clamp consisting of an open frame whose members are a single unit and connected with relative portions of the box providing a member within the box for the attachment thereto of an article to be supported and exhibited, 10 said frame having means thereon embracing an edge portion of a wall of the box whereby lateral shifting of the frame is prevented, 15

3. A supporting and exhibiting device attachable to a box said device being formed as a single integral unit and consisting of a frame constituting a clamp whose members are partly within and partly without the box, and engage two adjacent sides thereof, 20 25 the terminals of said frame being connected on the exterior of the box.

4. A supporting and exhibiting device attachable to a box, the same consisting of a frame constituting a clamp which is adapted to embrace portions of the bottom and side of the box, and formed of an exterior length adapted to be rested on the outer face of said side, and an inner length adapted to occupy the box within said side, said 30 frame having at one corner means to clamp an edge of the box, said inner length providing means for attachment thereto of articles placed in the box. 35

5. A supporting and exhibiting device attachable to a box consisting of a frame of a continuous piece of material and adapted to embrace portions of the bottom and side of the box, a member of said frame being adapted to be supported on said side, and another member being within the box and adapted to be supported on said bottom, and said frame having means for connecting its members, said frame constituting a clamp. 40 45
